UNITED STATES PATENT OFFICE.

PETER A. DEMUTH, OF COLOME, SOUTH DAKOTA.

BROODER.

Application filed July 21, 1924. Serial No. 727,304.

This invention relates to chicken brooders and has for its object the provision of a simple and inexpensive device which may be readily manufactured and set up and which will efficiently protect young chickens from cold weather. The invention seeks to provide a device in which proper ventilation will be effected and which will permit free access of the chickens to and from the device and in which the interior will be of such construction that repairs or renewal of parts may be easily effected.

The invention is illustrated in the accompanying drawings, in which Figure 1 is a view, partly in elevation and partly in section, of one form of my improved brooder; and

Fig. 2 is a plan view, partly broken away, of one brooding chamber shown in Fig. 1. In carrying out my invention, I provide a housing 1 which may be of any desired form and is preferably circular, as such form may be more easily produced than an angular form. The housing comprises a vertical wall defining a shell having an open bottom and adapted to rest directly upon the ground or the floor of a chicken house. This wall is provided with one or more openings 2 constituting doorways through which the chickens may pass to and from the brooding chamber, and a top 3 is supported by the wall and extends across the entire chamber. The doorway 2 provides a ventilating opening but, to assure complete ventilation, openings, indicated at 4, may be formed in the wall near the lower edge thereof at such intervals as may be desired, and in the roof or top 3 a ventilator 5 is fitted, which ventilator, as shown most clearly in Fig. 2, is of a damper construction whereby the circulation of air may be controlled. Upon the inner side of the wall 1, I secure an annular bracket or rail 6, preferably formed from an angle bar, as shown clearly in Fig. 1, and in

the overhanging branch of this bracket or rail I mount hangers 7 of which any number may be employed as may seem most advantageous. These hangers are threaded in their upper end portions, as shown at 8, and nuts 9 are mounted upon the upper extremities of the hangers and turned home against the bracket or rail 6 so that the hangers will be properly secured and firmly supported. The lower ends of the hangers are turned laterally outward to provide feet 10, and to the said feet a hoop or ring 11 is secured. A curtain

12 of textile fabric, such as a woolen blanket, is secured to and depends from the hoop, and a cover 12' of like material is also secured upon and extended over the area defined by the hoop. The cover is, of course, circular to conform to the shape of the wall 1 and the hoop which is located in proximity to the wall. A hem is formed on the cover to receive and contain the hoop and the curtain 12 is attached to the said hem. The hem may be formed by stitching in a well-known manner and the curtain likewise attached to the hem.

In the larger sizes of the brooder illustrated in the drawing, I provide two brooding chambers which are duplicates in construction and between the said chambers I arrange a stove or heater 13, the upper portion of which is constructed to form a boiler or water chamber of any approved form. Extending from the boiler or water chamber 14 into each brooder chamber are circulating heating pipes 15 which are arranged at the center of each chamber in the form of a radiating coil 16, it being readily noted upon reference to Fig. 1 that the circulating pipes are disposed with their terminals in different horizontal planes of the boiler so as to provide for effectual and ready circulation of the water as the same becomes heated so that the hot water will flow into the radiating section 16 and the colder water will gravitate back to the boiler. To support the radiating section 16 within the brooding chamber, beams 17 are secured in the wall 1 and extend across the brooding chamber, as clearly shown, it being noted that a pair of beams is provided for each radiator and they are spaced apart so as to extend under the end portions of the radiator and thereby effectually support the same without obstructing the circulation of warm air within the brooding chamber.

In use, the air within the brooding chamber will be effectually raised in temperature by the heat thrown out by the circulating pipes and the radiator sections of the same within the brooding chamber and will circulate above the cover 12' so that all chilled air within the brooding chamber will be driven out and the fresh air flowing into the same will be raised to a proper temperature to maintain the healthy condition of the chickens. The fabric cover 12' will extend over the entire brood of chickens so as to protect them from direct contact with the

highly heated air from the hot water pipes and thereby avoid overheating of the chickens. At the same time, the woolen fabric of the cover will absorb and retain sufficient heat to prevent chilling of the chickens in the event that the fire in the stove or heater 13 should get low. The curtain 12 will hang close to the wall of the brooding chamber and will thereby prevent the young chickens from coming into direct contact with the wall which is preferably of sheet metal and, consequently, prevent chilling of the chickens from such source. It will be further noted that the curtain hangs freely so that it will yield readily to the chickens which may be passing into or out from the brooding chamber and will also prevent the air flowing in through the ventilating openings 4 from playing directly upon the brood. The device is exceedingly simple in construction and access may be easily had to any of the parts which may need repairing or renewal.

Having thus described the invention, I claim:

A brooder comprising a housing including a circumscribing wall and a removable top, said wall having a passage in its lower portion, an annular rail secured against the inner face of said wall intermediate its depth and having a flange projecting inwardly therefrom, a hover within said housing consisting of a hoop conforming to the contour of said wall and extending adjacent thereto, a textile cover stretched over said hoop and having its marginal portions secured about the hoop, a circumferentially extending curtain depending from the marginal portions of said cover and disposed close to said wall, hanger rods disposed vertically and having their lower ends secured to said hoop and their upper end portions threaded and projecting through openings in the flange of said rail, and nuts screwed upon the projected upper ends of said rods and resting upon said flange to support the rods and permit vertical adjustment of the hover and removal of the hover with the housing.

In testimony whereof I affix my signature.

PETER A. DEMUTH. [L. s.]
